ELECTRICAL INDICATING MEANS

Harrison F. Edwards, Pleasantville, N.Y., assignor to Simmonds Precision Products, Inc., Tarrytown, N.Y., a corporation of New York

Filed Mar. 16, 1965, Ser. No. 443,766

4 Claims. (Cl. 340—373)

This invention relates to indicators and is particularly suitable for displaying the result of an operation of a remotely located device such as a digital readout meter which is capable of responding to a plurality of discrete voltages.

This application is a continuation-in-part of application Serial No. 107,224, filed May 2, 1961, by the same inventor, entitled "Reluctance Flag."

The general object of the invention is to provide a remotely controlled indicator operating on the hitherto known magnetic principle that a flux field tends to establish a particular path that will contain certain flux lines.

Another object of the invention is the inclusion of a minuscule assembly of elements for an electromagnetic indicator capable of operating on either A.C. or D.C.

According to the present invention, a field assembly comprising a coil winding is sandwiched between a pair of spaced substantially parallel plates of magnetizable material and, thereafter, positioned between a frame element which is generally U-shaped in configuration and has parallel spaced apertured upstanding legs. A non-magnetic rotary member is confined between the upstanding legs of the frame above the coil winding. A hairspring is associated with a portion of the rotary member and the frame to bias the rotary member to a position of rest. A suitable band of magnetizable material is affixed to and encircles the rotary member, and, upon energization of the coil winding of the electromagnetic field assembly from a remote source, effects a rotative movement of the rotary member thereby positioning the widest extent of the band adjacent to the coil winding.

In the preferred embodiment of the invention, the magnetically influenced band, and, particularly, in a flat development thereof, there are a plurality of laterally extending teeth forming the termini of one end of said band, the root portions of which merge with the other end of said band.

Also in accordance with the teaching of this invention, there is provided an overlying lamina in the form of an indicia carrying band that is placed about the rotary member and over the aforesaid toothed magnetic band so that, under the influence of the coil winding, the rotary member will revolve a predetermined distance to provide an appropriate signal.

Other objects and advantages of this invention will become apparent from the following description when read in the light of the attached drawing in which:

FIG. 1 is an exploded view of the elements from which the indicator is assembled;

FIG. 2 is a flat development of the metal laminate underlying the indicator lamina;

FIG. 3 is a perspective view of the completely assembled electromagnetic indicator;

FIG. 4 is an exploded view of the coil assembly; and

FIG. 5 is a side elevational view of the rotary support.

Referring to FIG. 1, the reference numeral 25 indicates a generally U-shaped frame, the upstanding legs of which are suitably apertured for purposes that will be apparent as the specification progresses.

The spool-like element 26, also referred to herein as a rotary member, should be non-magnetic, and accordingly, it may be produced from any number of synthetic or natural resins, for example, acrylic, alkyds, amino resins, epoxy resins, polyethylene, polyamides, phenolic resins,

2

polyesters, polystyrene and other vinyl polymers and copolymers.

A coil winding 34 provided with customary leads is sandwiched between pole plates 35-35 of magnetizable material and while retained in juxtaposed relation a low carbon steel core is introduced through the axially aligned apertures of the coil and the plates. In a preferred assembly operation, particularly since the completely assembled indicator is minuscule, an extension 36' is provided on one end of the core to facilitate assembly. Subsequent to insertion in the aligned openings of the coil and plates one end of the core is swaged over as represented at 36, and the extension 36', thereafter, broken away from the free end of the core where it passes through the adjacent plate. After the elements comprising the field assembly are unitized, it is placed into the upstanding legs of the frame 25. This will be best understood by referring to FIG. 3.

The rotary member shown in the exploded view of FIG. 1 and also shown in FIG. 5, may be produced by extrusion molding, etc., and is provided with a cylindrical body portion 27 and an enlarged collar element 28. The diametrically opposed ends of the rotary member are also shown as having axially aligned reduced portions 29 and 30, respectively. The spool-like body is apertured in any suitable manner during or after manufacture and adapted to receive a polished steel pindle 31, which is positioned in the apertures 32 and 33, respectively, to thereby support the spool for relative rotation between the upstanding arms of the frame 25.

Prior to assembly of the aforesaid spool element within the confines of the arms of frame 25, the remainder of the elements shown in the exploded view must be assembled therewith.

The hairspring 37, which is made of phosphor bronze or any other suitable spring-like material that is non-magnetic and, accordingly, not influenced by the electromagnet, is fastened about the collar 29. The depending free end or leg 38 of the hairspring is secured to pin 39 which projects inwardly of one of the arms of frame 25.

They alloy metal magnetic band 40, shown best in the flat development of FIG. 2, generally approximates a pair of sawteeth. In the exploded view, the axially extending tapered elements 41 form the termini at one end of the magnetic band 40 and the apexes are arranged in circumferentially spaced relation while the bases thereof merge into the other end of said band.

The magnetic band 40 is wound about the cylindrical body 27 of the spool in any preferred manner. Thereafter, a decal 42 bearing suitable informative indicia is secured about magnetic band 40 by means of a self-adhesive or any other preferred manner. The decal is colored in a manner such as by having a black matte finish to provide contrast between it and the indicia signal "OFF."

It is believed to be apparent to those skilled in the art that upon energization of the coil winding 34 of the field assembly the flux field between the pole plates 35 will seek out a path of least reluctance which in the present device is produced by the magnetic attraction effect on the magnetizable band 40 which rotates the cylinder 27 to a position where the band has the greatest amount of flux lines passing therethrough. This position would define in minimum air gap between the pole plates 35 wherein the base portion of the sawtooth-shaped band is adjacent the coil winding 34. In this position, only the black matte portion of the decal is visible. The inwardly extending stop pin 45 shown assembled with an arm of the frame 25 (FIGS. 2 and 3) is of sufficient length to project into the path of travel of the rotary member. The cylinder 27 is provided with a shelf 43

that engages the stop pin 45 to thereby limit revolution of the rotary member to substantially ninety degrees from an indicia displaying position to a non-displaying position or vice versa.

From the foregoing discussion it is apparent that considerable modification of the features of this invention is possible but it is to be understood that the invention is not limited to this precise device and form of apparatus and that changes may be made therein without departing from the scope of the invention which is defined in the appended claims.

I claim:

1. An indicating device comprising a U-shaped frame including a base portion and upstanding spaced legs, a field assembly including laterally spaced magnetizable plates with an electromagnetic coil winding disposed therebetween, said spaced plates being confined between said spaced legs with the axis of said coil being normal to said plates, a non-magnetic rotary member of approximate cylindrical shape, pintle means for rotatably mounting said member about an axis parallel to said plates adjacent the ends of said legs of said U-shaped frame, a sawtooth shaped band of magnetizable material surrounding the periphery of said rotary member, and indicia bearing element overlying said band, and spring means cooperating with one end of said rotary member and one of said spaced legs of said U-shaped frame for biasing said member to a fixed position wherein said band presents a substantially maximum air gap between said plates.

2. An indicating device as claimed in claim 1 wherein the sawtooth shaped band comprises axially extending tapered elements which form the termini of one end of said magnetic band the apexes of which are in circumferentially spaced relation and the bases of which merge adjacent to the other end of said band.

3. An indicating device as claimed in claim 1, wherein the non-magnetic rotary support comprises a substantially cylindrical spool-like element.

4. An indicating device comprising a U-shaped frame including a base portion and upstanding spaced legs, a field assembly including laterally spaced magnetizable plates with an electromagnetic coil winding disposed therebetween, said spaced plates being confined between said spaced legs with the axis of said coil being normal to said plates, a non-magnetic rotary member of approximate cylindrical shape, pintle means for rotatably mounting said member about an axis parallel to said plates adjacent the ends of said legs of said U-shaped frame, a sawtooth shaped band of magnetizable material surrounding the periphery of said rotary member and spring means cooperating with one end of said rotary member and one of said spaced legs of said U-shaped frame, said spring means biasing said member in a fixed position wherein said band presents a substantially maximum air gap between said plates.
